HYDRAULICALLY OPERATED GRINDING
MACHINEWallace H. Wood, Worcester, Mass., assignor to
Norton Company, Worcester, Mass., a corpora-
tion of Massachusetts

Application August 23, 1934, Serial No. 741,119

12 Claims.

This invention relates to grinding machines, and more particularly to a hydraulic table reciprocating mechanism and wheel feeding mechanism for precision grinding machines.

5 Heretofore, various mechanisms have been devised for reciprocating either the work support or the wheel support relative to the other member by a fluid pressure mechanism including a reversing valve to change the direction of movement of the movable member. Many of these mechanisms have been unsatisfactory for use in a grinding machine, due to the fact that when the table is run at a fast speed, there is considerable shock and vibration transmitted to the machine parts when the reversing valve is suddenly shifted to a reverse position, rapidly cutting off the fluid under pressure on one side of the system and transferring it to the other side. Also, it has been found that with previous mechanisms, when 10 the table is run at a very slow speed, the movement of the reversing lever by the slowly moving table carriage has been insufficient to carry the reversing lever past the central or neutral position so that it may be shifted into a reverse position.

15 Further hydraulic table reciprocating mechanisms have been developed, in which some of the difficulties experienced in the previously described mechanisms have been somewhat overcome. It has been common practice for some time in such hydraulic systems to provide a pilot valve which is controlled by movement of the moving member to admit fluid under pressure so as to cause the reversing valve to shift under the influence of fluid pressure. Such mechanisms have proven to be fairly satisfactory, but have resulted in more or less complicated fluid pressure systems which required the use of a plurality of valves and also numerous pipe connections to operatively connect the various elements of the system, thereby giving opportunity for air and oil leaks in the system which detrimentally affect the operation of the mechanism.

20 A further difficulty experienced in hydraulically driven cylindrical grinding machines, particularly machines adapted for traverse grinding, resides in the lack of an adequately controlled wheel feeding mechanism which has the necessary adjustments to permit not only the amount of feed but also the timing of the infeed relative to the table traverse and reversal to be controlled.

25 Another difficulty experienced with hydraulically driven machine tools is that air creeps into the fluid pressure system, thereby displacing a certain amount of oil. Air being more compressible than

the oil prevents the system from running smoothly, since when fluid under pressure is suddenly changed in direction of flow to reverse the movement of parts, the compression of the air in the oil serves as a variable to prevent smooth operation of the moving parts. This leakage of air into the system not only causes a jerky movement of the reciprocable parts but the extent of movement of the reciprocable table varies considerably as the amount of air leaking into the system varies. 10 Air may leak into the system through various ways—either through leaky joints in the piping or valves, or if the oil in the reservoir becomes at all foamy, then air is pumped into the system with the oil.

15 It is the primary object of this invention to eliminate the difficulties experienced with the previous mechanisms and to provide a fluid pressure operated mechanism in which a single valve serves to combine the functions of a reversing valve and a pilot valve within a single valve casing.

20 It is another object of this invention to provide a fluid pressure system with a combined pilot-reversing valve and a speed control valve within the same valve casing.

25 It is a further object of this invention to provide a fluid pressure operated dwell control device which serves to cause a sufficient dwell in the table movement to allow the work to rotate through one complete turn before the table starts traversing in the reverse direction.

30 It is another object of this invention to provide a shuttle valve shunted around the main control valve to produce a predetermined dwell of the table at reversal.

35 It is a still further object of this invention to provide a fluid pressure system with a combined fluid pressure pilot-reversing valve and a speed control valve which are arranged so that when the fluid pressure in the system is cut off to stop the table movement, a by-pass is opened, permitting fluid to pass readily from one end of the fluid pressure cylinder to the other so as to enable the carriage to be traversed manually without the necessity of overcoming the pressure in the system.

40 It is an object of this invention to provide a hydraulically actuated wheel feed mechanism in which both the extent of infeed as well as the time of infeed relative to the table traverse and reversal may be accurately controlled.

45 It is also an object of the present invention to provide a readily accessible bleeding device associated with the cylinder to draw off fluid

55

from the upper portion of the main cylinder, so that any air entrapped within this portion of the system may be readily removed.

Other objects will be apparent from the foregoing disclosure. One embodiment of this invention has been illustrated in the drawings, in which like reference numerals indicate like parts:

Fig. 1 is a front elevation of a grinding machine embodying this invention;

10 Fig. 2 is a combined fragmentary sectional and diagrammatic view, on an enlarged scale, showing the valves and piping arrangement for the fluid pressure system;

Fig. 7 is a detail view of the adjustment for the speed control valve;

30 Fig. 8 is a fragmentary, cross-sectional view, taken approximately on the line 8—8 of Fig. 5, showing the spring connection between the parts of the reverse lever; and

35 Fig. 9 is a fragmentary view of a modified construction, partly in section, showing a fluid pressure operated dwell control apparatus.

One embodiment of the invention has been illustrated in the drawings, in which a cylindrical type grinding machine is provided with a hydraulically operated table traversing mechanism. The table may be traversed or reciprocated at a desired traversing speed, then reversed and allowed to dwell a sufficient extent to allow the work to rotate once before the table starts its motion in the reverse direction. A grinding wheel feeding mechanism is provided which is hydraulically actuated and is preferably operated by means of the table reversing lever which in turn actuates a micrometer feeding mechanism to cause a rotation of a feed screw and thereby produce an infeeding of the grinding wheel while the table is at the end of its reciprocatory stroke.

This invention further includes a combined pilot and reversing valve formed as a single valve unit, in which the end chambers of the reversing valve serve and function as a pilot valve to cause a reversal of the reversing valve by means of fluid under pressure. The combined pilot-reversing valve is supplemented by an auxiliary 60 shuttle valve, which is preferably shunted around the reversing valve and arranged to cause the table to dwell when the reversing valve is shifted from one position to the other a sufficient length of time to allow the work piece to rotate one complete turn before the table starts its movement in the reverse direction, so as to allow the grinding wheel to grind the entire surface of the work on each relative traverse of grinding wheel and work support.

70 As illustrated in the drawings, the machine embodying this invention comprises a base 10 which supports a work table 11 on the usual V-way and flat-way (not shown) for a longitudinal, reciprocating movement relative to the base. A headstock 12 and footstock 13 are mounted on the

table 11 and are arranged to rotatably support a work piece 14 in operative relation with a rotatable grinding wheel 15. The grinding wheel 15 is rotatably supported on a wheel slide 16 of the usual type, such as shown in the expired patent to Norton No. 762,838 dated June 14, 1904. In the preferred form, an electric motor 20 is mounted on the wheel slide 16 and is provided with a pulley 21 which is connected by a driving belt 22 with a pulley 23 on the end of a wheel 10 spindle 24.

15 A fluid pressure mechanism is provided to reciprocate the work table 11. In the form illustrated, a cylinder 30 is fixedly mounted to the under side of the table 11. The cylinder contains a pair of spaced pistons 31 and 32 which are connected by a pair of hollow piston rods 33 and 34 respectively with a pair of hollow brackets 35 and 36 respectively which are fixedly mounted on opposite ends of the base 10.

20 In the preferred construction, the base 10 is formed as a hollow, box-like construction in which the lower portion serves as a reservoir 40 for the fluid pressure system. Fluid is drawn from the reservoir 40 through a pipe 41 by a 25 pump 42 and is forced through a pipe 43 and a pipe 44 to a table control valve 45. A fluid pressure relief valve 46 is provided in the pipe 44 and is arranged to allow fluid under pressure to by-pass through a pipe 47 and return to the 30 reservoir 40 in case the pressure within the system increased above a desired pressure.

25 To attain the primary object of this invention, the control valve 45 is provided which combines the functions of a reversing valve and a 35 pilot valve, so that a lever actuated by the table movement serves to move the valve only to a center position and then fluid under pressure serves to move the reverse valve into a reverse direction, producing a smooth reversal of the 40 table movement without the necessity of providing a complicated series of valve mechanisms and pipe connections. In the form illustrated, a piston type valve is provided including a movable 45 valve member 49 having a plurality of valve pistons 50, 51, 52, 53 and 54 integrally formed thereon. Fluid under pressure from the pump 42 is forced through the pipe 44 into a chamber 58 within the valve casing 45. Assuming the valve to be in a central or neutral position, fluid under 50 pressure is conveyed from the chamber 58 through ports 59 and 60 into valve chambers 61 and 62 respectively. The valve chambers 61 and 62 are formed between the valve pistons 51 and 52, 53 and 54 respectively.

55 In the position of the valve illustrated in Fig. 5, fluid under pressure passes from the valve chambers 61 and 62 through ports 64 and 65 respectively into chambers 66 and 67, then through pipes 68 and 69 respectively, through brackets 60 35 and 36, hollow piston rods 33 and 34 respectively, into cylinder chambers 70 and 71 respectively and thereby to balance the pressures against opposite ends of the cylinder so as to hold the work supporting table in a stationary 65 position. In actual operation, however, the parts are only in position shown in Fig. 5 for an instant during reversal of the table.

60 As illustrated in Fig. 5, fluid under pressure may pass from valve chambers 61 and 62 through 70 the ports 75 and 76, through ports 77 and 78 into valve chambers 79 and 80. The valve chambers 79 and 80 are formed between valve pistons 50, 51 and 53, 54 respectively. Fluid under pressure passes from the chambers 79 and 80, through 75

ports 81 and 82 into small reservoirs 83 and 84. The overflow from reservoirs 83 and 84 is returned to the reservoir 40 in the base. A pair of oil grooves 85 and 86 are connected with the reservoirs 83 and 84 and serve as an oil seal around the valve pistons 50 and 54.

The effective areas of valve pistons 50 and 54 is considerably less than the effective areas of valve pistons 51 and 53 respectively. By providing the differential in the pressure areas between these pistons, the chambers 79 and 80 serve to function as a pilot valve and cause a reversal of the reversing valve under the influence of fluid pressure whenever the valve is moved to a position slightly by the center position, as shown in Fig. 5; that is, so that either the port 77 or the port 78 is cut off to a greater extent from the other, allowing fluid under pressure to flow into either chamber 79 or 80. Due to the differential piston areas, the fluid under pressure entering chambers 79 or 80 serves to move the valve piston 49 either toward the right or toward the left, as viewed in Fig. 5.

Speed control valve

A speed control or throttle valve 90, as illustrated in Fig. 5, is formed integrally with the valve member 45. As illustrated in the diagrammatic showing in Fig. 2, the valve 90 is shown as a separate valve unit. The valve 90 is preferably located in the exhaust side of the system so as to maintain a uniform fluid pressure on the operative side of the main cylinder. This valve comprises a valve stem 91 which is provided with valve pistons 92 and 93. The casing for the valve 90 is provided with a V-shaped port 94 which is located at one end of a pipe or passage 95, conveying fluid from either of the valve chambers 61 or 62. A passage or outlet pipe 96 serves to exhaust fluid from a throttle valve chamber 97 into the reservoir 40 within the base of the machine.

The throttle valve is arranged so that it may be moved longitudinally from a full line position (Fig. 2) to a dotted line position. The valve is provided with an actuating knob 99 on the front end of the valve stem 91, which permits the valve to be rotated. In the preferred construction, the end of the valve piston 93, instead of being a plane surface at right angles to the axis of the throttle valve, is arranged at an angle thereto. By providing an angularly positioned end surface to the valve and rotating the valve member, it is possible to obtain a fine adjustment by cutting off more or less of the V-port 94 to precisely regulate the exhaust of fluid from the system and thereby permit a fine regulation of the table speed.

In order that the valve piston 93 may be maintained in the desired adjusted position so as to enable the table to be stopped and started as desired without changing the speed adjustment, a serrated or notched portion 100 is provided and a spring-pressed pawl 101 is carried by the valve casing 90, so that when the knob 99 is turned to adjust the valve piston 93 to give the desired table speed, the pawl 101 engaging notches in the portion 100 serves to hold the piston in its adjusted position, so as to permit moving the valve stem 91 by means of the control lever 103 to start and stop the table movement without upsetting the adjustment of the valve.

To permit the valve piston 93 to be quickly and accurately located in a predetermined position to produce a predetermined table speed, an ad-

justing screw 102 is provided in the sleeve 106 and is arranged to engage a fixed stop surface 102a on the knob 99. By adjusting the screw 102 relative to the sleeve, the angular position of the valve piston 93 may be varied, so that the valve, when adjusted, may be turned to a second speed, for example, a fast speed, and then readily turned back to a predetermined adjusted table feed by merely turning the knob 99 until the stop screw 102 engages the stopping surface 102a.

A lever 103 is pivotally mounted on a stud 104 on the base of the machine 10 to permit rapid movement of the valve stem 91 to start and stop the table movement. The lever 103 is provided with an aperture 105 fitting loosely around a sleeve 106 which is mounted on the valve stem 91. Trunnion pins 108 are provided at opposite sides of the aperture 105 on the lever 103 and are arranged to engage vertical slots 109 in the sleeve 106. It will be readily apparent from the foregoing disclosure that when the throttle valve control lever 103 is in the position as indicated in full lines in Fig. 2, the valve stem 91 is positioned so that valve piston 93 uncovers a portion 25 of the V-port 94, allowing the table to move at a predetermined speed. By moving the lever 103 into position 103a, as indicated in broken lines in Fig. 2, the valve piston 93 may be moved into position 93a, closing the V-port 94 and thereby 30 stopping the table movement.

Fluid by-pass

When the throttle valve is in a closed position, stopping the table movement, it is desirable to provide a suitable fluid by-pass whereby fluid may readily pass from one end of the cylinder chamber to the other. In the preferred construction, a passage or pipe 110 is provided to connect the pipe 69 and valve chamber 62 with a passage 111 provided as an extension of the pipe 68, so that when the throttle valve 90 is in a closed position, as indicated by the broken lines in Fig. 2, fluid may readily pass from cylinder chamber 70 through pipe 68, pipe 111, through a valve chamber 112 between pistons 92 and 93, out through pipe 110, through pipe 69, and into the cylinder chamber 71. This by-pass in the throttle valve interconnects the cylinder chamber 70 and 71 so that when the fluid pressure system is shut off by closing the throttle and control valves 91, the table 11 may then be moved manually, if desired.

Manual traverse

In order to move the table 11 to traverse the table manually, a suitable hand wheel 120 is mounted on the front of the machine base. This wheel rotates a gear 121 meshing with a gear 122 on the shaft 123. The shaft 123 in turn carries a gear 124 meshing with a rack 125 depending from the table 11. It will be readily appreciated from the foregoing disclosure that when the lever 103 is moved into a position to close the control valve, the table 11 may then be traversed longitudinally by manual rotation of the wheel 120. As the table is moved under manual control, fluid within the chambers 70 and 71 will readily bypass through the pipes, as above described, so as not to retard the movement of the table.

Wheel feed mechanism

The grinding wheel 15 and its supporting slide 16 may be fed toward and from the work support by a pawl and ratchet wheel feeding mecha-

nism, such as shown, for example, in the expired U. S. patent to Norton No. 762,838 dated June 14, 1904. As illustrated in the drawings, this mechanism may comprise a feed wheel 126
5 which carries a pinion 127 meshing with a gear 128 on a feed screw shaft 129. The feed screw 129 (not shown) meshes with a half nut (not shown) depending from the wheel slide 18. This feed screw and the half nut have not been illustrated in detail, since they do not constitute any part of the present invention. For details as to the arrangement of these parts, reference may be had to the prior patent above mentioned. The wheel feed 126 is provided with a micrometer
10 adjusting mechanism which permits a fine adjustment of the stopping position of the wheel feed.

Automatic reversal-work table

20 A suitable reversing mechanism is provided to change the direction of the table movement, as desired. In the preferred construction, adjustable dogs 130 and 131 are adjustably mounted in a T-slot 132 on the table 11. The dogs 130 and 25 131 are arranged to engage the upper end of a reverse control lever 133 which is pivotally mounted on a stud 134 on the base of the machine. The lever 133 is operably connected to a projection of the valve stem 49.

30 In order that the table may be reversed with a minimum amount of vibration, it is desirable to provide a lost motion connection between the reversing lever and the reversing valve, so that during the initial movement of the reversing lever
35 under the influence of the table dogs, the valve is not moved. This mechanism preferably comprises a short lever 138 fixedly keyed to the inner end of stud 134. A similar short lever 139 is rotatably mounted on the stud 134 and is supported thereon by means of a bushing, so that the lever 139 is free to oscillate relative to the stud 134. The lever 138 carries a pin 140 engaging a groove 141 in an extended portion of the valve stem 49. The lever 138 is provided with an aperture 144, within which is located a pin 145 which
40 is fixedly mounted to the lever 139. The lower ends of the levers 138 and 139 are provided with enlarged portions 150 and 151 respectively, each of which is provided with a semi-cylindrical aperture 152 and 153. A spring 155 is provided within the semi-cylindrical apertures 152 and 153 and serves to hold the levers normally in a definite relation to each other and also aids in actuating the reversing valve through a portion of its movement.

Assuming the parts of the reversing mechanism to be in the positions illustrated in Fig. 3, the table is moving in a direction toward the left, as viewed in Fig. 1. This movement continues until the reversing lever 133 is moved from broken line position 133 (Fig. 3) into full line position 133a (Fig. 3) which serves to actuate the lever 138 through its lost motion movement until the aperture 144 engages the pin 145. This movement of the lever 138 serves to put the spring 155 under tension, and when the aperture 144 engages the pin 145, continued movement of the table serves to throw the reversing valve stem 49 into a neutral or central position indicated in Fig. 5— where the pressures are balanced to opposite sides of the main cylinder 30. The tension of spring 155 then moves the valve stem 49 a further distance toward the right, partially closing the port 78. This same movement causes the valve piston 51 to uncover the port 77, decreasing the fluid

pressure passing into chamber 80 and increasing fluid pressure passing into valve chamber 78. It should be noted that the valve pistons 50 and 51 are provided of a different cross-sectional area, and fluid under pressure entering the chamber 78 serves through the differential pressure area on the pistons 50 and 51 to move the valve stem 49 towards the right, as viewed in Fig. 5, to throw the valve into its extreme reverse position and thereby cause a reversal in direction of movement of the fluid under pressure to pass the same to the opposite end of the main driving cylinder 38 and thereby cause the table 11 to move in the opposite direction.

Due to the differential in the pressure areas 15 between the valve pistons 50 and 54 and 51 and 53 respectively, the chambers 79 and 80 function as a pilot valve to cause a reversal of the reversing valve under the influence of fluid pressure. The reversing lever 133 serves only to cause 20 the reversing valve to move to its central or neutral position, as is illustrated in Fig. 5, and the spring 155 then being under tension serves to throw the reversing valve slightly off center to change the respective openings of the ports 25 77 and 78 and cause the fluid under pressure to operate through the chambers 79 and 80 to cause a fluid pressure reversal of the reversing valve, thereby combining the functions of a reversing valve and a pilot valve in a single valve unit, eliminating the piping connections and losses due to passages between the various valves, as experienced heretofore. 30

Wheel feed actuating mechanism.

It is desirable to provide a suitable mechanism for actuating the wheel feeding mechanism in timed relationship with the movement of the work supporting table. In the preferred construction, a fluid pressure mechanism is provided which is operated by and in timed relationship with the movement of the reverse control lever. As illustrated in the drawings, this mechanism comprises a cylinder 160 having a piston 161 connected by a piston rod 162 with a link 163 which is pivotally connected to a pawl actuating slide 164 by a stud 165. This slide 164 also carries a pivotally mounted feed pawl 166 which is of a construction substantially the same as that shown in the above mentioned prior patent.

In order to obtain actuation of the pawl 166 in timed relationship with the reversing lever 133, a valve 170 is provided with a movable valve piston 171, the upper surface of which is formed as an inverted V-shaped surface 172 adapted to be 55 engaged by and moved by an arrow point 173 which is mounted on the lower end of the reverse lever 133. A spring 174 within a hollow central aperture in the piston 171 serves normally to hold the arrow point in an uppermost position. An adjustable stop screw 175 mounted on the base of the machine serves to limit the upward movement of the valve member 171. A pipe 177 is connected with the fluid pressure pump 42 to convey fluid under pressure to a valve chamber 178 which in the upper position of the valve, as illustrated in Fig. 2, passes fluid under pressure through a passage 179 into a cylinder chamber 180 to move the piston 181 and hold it in its lower position with the pawl withdrawn also to 70 its lower position. In the position of the parts as illustrated in Fig. 2, fluid under pressure is exhausted from a cylinder chamber 184 through a passage 185, a valve chamber 186, and through an exhaust pipe 187 into the reservoir 40 in the 75

base of the machine. When the table 11 reaches the end of its stroke, one of the adjustable dogs 130 or 131 moves the reversing lever 133 to actuate the reversing valve to change the direction of movement of table 11. During the initial part of this rocking movement of the reverse lever 133, the arrow point 173 rides on the V-surface 172 causing a downward movement of the valve member 171. This movement serves to partially close the passage 179 and open the passage 185, admitting fluid under pressure to the cylinder chamber 184 to cause an upward movement of the piston 161 and also of the feed pawl 166 to start a feeding movement. This downward movement of the valve 171 continues until the reversing lever passes the high point on the arrow and inverted V; and as the lever swings by the central position, the released tension of the spring 174 serves to return the valve member 171 to its uppermost position, cutting off fluid under pressure from the passage 185 and admitting all of the fluid under pressure to the passage 179 to cause a downward movement of the piston and also a corresponding downward feeding movement of the feed pawl 166 in contact with the ratchet or feed wheel 126. It will be readily appreciated from the foregoing disclosure that at each actuation of the reversing lever 133, the feed pawl will be moved through a predetermined extent to cause the desired infeeding movement of the grinding wheel at each end of the table stroke.

Feed adjustment

The extent of the feeding movement may be adjusted by means of an adjustable stop 190, which is slidably adjustable relative to an elongated slot 191 in the link 163. The stop 190 is arranged to engage a stopping surface 192 at the lower edge of the support for the slide 164. By adjusting the position of the stop 190 relative to the link 163, the extent of upward movement of the index pawl may be adjusted to produce the desired infeeding movement at each end of the table stroke.

A further adjustment is also provided on the reversing lever 133. In the preferred construction, the arrow point 173 is adjustably positioned on the lever 133 by means of an adjusting screw 200 and a stop screw 201. This adjustment of the arrow point relative to the pivot 134 serves to vary the extent of movement of the valve member 171 so as to permit varying the speed of movement of the index pawl. It will be readily seen from this construction that by permitting fluid under pressure to enter both the passage 185 and 179, and by varying the respective openings to these passages, a differential pressure is established between the cylinder chamber 180 and 184, which serves to regulate the speed of movement of the piston during the feeding movement of the pawl 166.

Dwell control

The fluid pressure system is so arranged that the table reversal takes place very rapidly and in some cases reverses so rapidly that the cylindrical piece of work being ground does not have an opportunity to rotate through one complete turn to allow the wheel to grind out before the table starts its movement in the reverse direction. In order to provide a slight but predetermined dwell sufficient to allow the work to rotate through one complete turn at the end of its stroke, a shuttle valve is provided which is preferably so

constructed and so connected in the system that upon reversal of the reversing valve the initial change in direction of fluid in the system moves through the easiest course and instead of being transmitted immediately to the opposite end of the cylinder serves to move a shuttle valve piston 205 which is slidably mounted within a cylinder 206. The opposite ends of the shuttle valve are connected by pipes 207 and 208 to the pipe lines 68 and 69 respectively. Each of these pipes 207 and 208 is provided with a shut-off valve 209 and 210 which permits the shuttle valve to be rendered operative or inoperative when desired.

The ends of the shuttle valve piston 205 are formed as frusto-conically shaped projections 211 and 212 which are arranged to enter a pair of chambers 213 and 214 in opposite ends of the shuttle valve cylinder 206. The chambers 213 and 214 with the cooperating projections 211 and 212 serve as dash pots to slow down the movement of the shuttle valve piston 205 as it approaches the end of its stroke within its cylinder. It should be noted in Fig. 9 that when the shuttle valve reaches the extreme end of its stroke, the projection on the right-hand end of the piston provides only a slight clearance between it and its mating chamber within the shuttle valve cylinder. By utilizing this construction, when the main reversing valve is shifted to its reverse position with the parts as indicated in Fig. 2, the instant the fluid under pressure is reversed in direction serves to cause the fluid to enter through the pipe 207 and into the chamber 213 to cause the throttle valve piston 205 to move toward the right as viewed in Fig. 9. This valve moves at first rapidly until the projection 212 starts to enter the chamber 214 at the right-hand end of the shuttle valve cylinder. As soon as the projection starts to enter the chamber, the opening permitting exhaust from the shuttle valve cylinder is gradually reduced, and the shuttle valve piston gradually slows down until it reengages the end of its cylinder. The time interval between the shifting of the reverse valve into its reverse position to stop and reverse the table and the actuation of the shuttle valve cylinder to the opposite end of the cylinder is just sufficient to allow the work to rotate through one complete turn while the table is at the end of its stroke. When the shuttle valve piston engages the end of its cylinder, the fluid under pressure is then applied in the reverse direction to the table traversing cylinder to start the table moving in the reverse direction. All of this movement is substantially instantaneous, but there is sufficient dwell provided by varying the size of the shuttle valve piston and its projection so as to enable the work to rotate through one complete turn before the table reverses in direction, so as to allow the grinding wheel to grind out at each longitudinal reciprocation thereof.

Bleeder system

In order to permit ready removal of air entrapped in the fluid pressure system, a bleeder system is provided including a port 220 and 221 located respectively at each end of the cylinder 30 at the upper edge of the cylinder. Any air leaking into the cylinder rises to the upper portion of the cylinder and may be readily withdrawn by opening a valve 222 and 223 to allow the air and adjacent oil to escape through a pipe 224 and return to the reservoir 40 in the base of the machine. By utilizing such an arrangement, it is possible to bleed the system of any air which

- may initially be found in the system, or which may leak into the system, thereby eliminating the undesirable effect of air pockets within the fluid pressure system.
- 5 The operation of this mechanism is readily apparent from the foregoing disclosure. After adjusting the table dogs 130 and 131 to give the desired length of table movement to traverse the wheel over the desired portion of the work and 10 adjusting the feed pawl actuating mechanism to give the desired extent and speed of movement of the pawl to feed the wheel into the work at the desired rate, the operator then moves the speed control lever 103 from the broken line position 15 103a (Fig. 2) into the full line position to open the V-ports 84 so as to allow exhaust of fluid from cylinder chamber 71, thereby permitting fluid under pressure entering the cylinder chamber 70 to cause the cylinder 30 and table 11 to 20 move in the direction of the arrows, as indicated in Figs. 1 and 2. The traversing movement of the table in this direction continues until table dog 131 engages reversing lever 133 and rocks the lever in a counterclockwise direction. This 25 movement of the lever serves to move the valve piston 48 into a central or neutral position, thereby admitting fluid under pressure equally to opposite ends of the cylinder 30. The released tension of the spring 155 then serves to move the lever 133 relative to the lever 138, and thereby causes the valve stem 48 to be moved in a further direction toward the right sufficient to move the valve pistons 51 and 53 from their central position, admitting fluid under pressure through port 77 into 30 the chamber 79, which, due to a differential area between the piston 50 and piston 51, serves to move the valve piston towards the right and causes a completion of the movement of the reverse valve under fluid pressure to pass fluid under 35 pressure into the cylinder chamber 71. This movement allows fluid under pressure within the cylinder chamber 70 to exhaust through the throttle valve V-port 84 to move the table 11 in the opposite direction.
- 40 45 At each end of the table stroke, the arrow point 173, as previously described, causes an actuation of the valve member 171 to cause a predetermined infeeding movement of the grinding wheel.
- 50 Having thus described my invention, what I claim as new and desire to secure by Letters Patent is:
1. A hydraulically operated grinding machine having a rotatable grinding wheel and a work support which are movable longitudinally and transversely relative to each other, a fluid pressure system including a piston and cylinder operatively connected to cause said relative movement, means including a piston type reversing valve to convey fluid under pressure to either end of said cylinder, means including a reversing lever and adjustable dogs arranged on the relatively movable members to shift said valve to a neutral or central position, and a resilient connection between said lever and valve to shift the reverse valve slightly beyond a neutral or central position to admit fluid under pressure into fluid pressure chambers in the ends of said reversing valve which serve to shift the valve 60 by fluid under pressure into a reverse position.
- 65 70 75 2. A hydraulically operated grinding machine having a rotatable grinding wheel and a work support which are movable longitudinally and transversely relative to each other, a fluid pressure system including a piston and cylinder op-

eratively connected to cause said relative longitudinal movement, means including a piston type reversing valve to convey fluid under pressure to either end of said cylinder, a reversing lever actuated by said table, and lost motion connections between said lever and valve including a spring, said parts being so arranged that the table movement serves to shift the lever to compress the spring and positively move the valve to a neutral or central position, the tension of 10 said spring being sufficient to move the valve slightly by the central position to open a port at one end of said valve and admit fluid under pressure directly from the pump to fluid pressure chambers in the ends of said valve which 15 serve to shift the valve by fluid under pressure into a reverse position.

3. A hydraulically operated cylindrical grinding machine having a rotatable grinding wheel and a work support which are movable longitudinally and transversely relative to each other, a fluid pressure system including a piston and cylinder operatively connected to reciprocate said table, means including a reversing valve arranged to convey fluid under pressure to either 20 end of said cylinder, means actuated by one of said movable elements to actuate said valve and cause a reversal in direction of movement of said member, and a shuttle valve which is operatively connected between opposite ends of 25 said cylinder to cause a predetermined dwell sufficient to allow the work to rotate one complete turn to grind out at the end of each table stroke.

4. A hydraulically operated cylindrical grinding machine having a rotatable grinding wheel 35 and a rotatable work support which are movable longitudinally and transversely relative to each other, a fluid pressure system including a piston and cylinder operatively connected to reciprocate said work support, means including a piston type reversing valve to convey fluid under 40 pressure to either end of said cylinder, means including a reversing lever actuated by said table movement to reverse said valve after the table has moved through a predetermined distance, 45 and a dwell control mechanism including a shuttle valve shunted between the opposite ends of said cylinder to cause a predetermined dwell of the table at each end of its stroke.

5. A hydraulically operated cylindrical grinding machine having a rotatable grinding wheel 50 and a work support which are movable longitudinally and transversely relative to each other, a fluid pressure system including a piston and cylinder operatively connected to reciprocate said 55 table, means including a reversing valve which is arranged to convey fluid under pressure to either end of said cylinder, means including a reversing lever for said valve, adjustable dogs on said table for actuating said lever and valve 60 to reverse the direction of movement of the table after it has traversed to a predetermined extent, a dwell control device including a shuttle valve which is arranged to cause a predetermined dwell at each reversal sufficient to allow the work 65 to rotate one complete turn before the table starts its movement in the opposite direction, and means to render said dwell control means inoperative when desired.

6. A hydraulically operated grinding machine 70 having a rotatable grinding wheel and a work support which are movable longitudinally and transversely relative to each other, a reversible mechanism including a reversing lever to cause said longitudinal movement, a feeding mecha- 75

nism including a pawl and ratchet to cause said transverse movement, a self-contained fluid pressure mechanism including a piston and cylinder operatively connected to actuate said pawl and ratchet, a control valve associated with said piston and cylinder which is actuated by said lever to operate the feeding mechanism to cause a transverse feeding movement when the reversing lever is shifted to change the direction of said longitudinal movement and means to adjust the extent of movement of said self-contained fluid pressure mechanism and also the extent of movement of said pawl so as to obtain a desired and predetermined transverse feeding movement at each reversal of the longitudinal movement.

7. A grinding machine comprising a rotatable grinding wheel and a work support which are movable longitudinally and transversely relative to each other, a fluid pressure system including a piston and cylinder operatively connected to reciprocate the work support, a reversing mechanism including a reversing valve which is actuated by movement of said support to cause a reversal in direction of movement of the same, a single control valve which is arranged so that in one position it allows free by-pass of fluid from one end of the cylinder to the other so that the table may be readily traversed manually and in the other position to throttle the exhaust of fluid from said cylinder and means to adjust said control valve so as to regulate the speed of said work support.

8. A grinding machine comprising a rotatable grinding wheel and a rotatable work support which are movable longitudinally and transversely relative to each other, a fluid pressure system including a piston and cylinder operatively connected to reciprocate the work support, a reversing mechanism including a reverse valve which is actuated by movement of said support to cause a reversal in direction of movement of the same, a control valve which is arranged so that in one position it allows free by-pass of fluid from one end of the cylinder to the other so that the table may be readily traversed manually and in the other position to throttle the exhaust of fluid from said cylinder, and means to rotate said control valve to regulate the speed of said work support.

9. A grinding machine comprising a rotatable grinding wheel and a work support which are movable longitudinally and transversely relative to each other, a fluid pressure system including a piston and cylinder operatively connected to reciprocate the work support, a reversing valve arranged to convey fluid under pressure to either end of said cylinder to reciprocate the work support, a reversing mechanism including a reversing lever arranged to reverse said valve to cause a predetermined reciprocation of the work support, a control valve which is arranged for both a rotary and an endwise movement which is arranged when in one position to allow free by-pass of fluid from one

end of the cylinder to the other to enable traversing the work table without the necessity of overcoming the fluid within the system and in a second position serves to throttle the exhaust of fluid from said cylinder, means to rotate said control valve so as to regulate the speed of movement of said work support and an adjustable stop to limit the rotary adjustment of said valve.

10. A fluid pressure table reciprocating mechanism comprising a reciprocable work table, a piston and cylinder operatively connected to move said table, a reversing valve arranged to reverse the direction of fluid under pressure to either end of said cylinder to cause a reciprocation of the table, a control valve in said system which is arranged in one position to permit by-passage of fluid from one end of the cylinder to the other and in a second position serves to throttle the exhaust of fluid from said cylinder, a manually operable lever which is arranged to move said valve from a by-pass to a speed control position, a V-port in said valve to permit a fine adjustment of the fluid exhaust line to enable the obtaining of the desired table speed, and a rotary adjustment for said valve to regulate the speed of movement of the table.

11. A hydraulically operated grinding machine having a rotatable grinding wheel and a work support which are movable longitudinally and transversely relative to each other, a reversing mechanism including a reversing lever to cause a longitudinal reciprocatory motion between the wheel and work support, a feeding mechanism including a pawl and ratchet to cause said transverse movement, a self-contained fluid pressure mechanism including a piston and cylinder operatively connected to actuate said pawl and ratchet, a control valve associated with said piston and cylinder, and an adjustably mounted 40 detent on said reversing lever to actuate said valve to cause a transverse feeding movement when the reverse lever is shifted to change the direction of said longitudinal movement.

12. A hydraulically operated grinding machine having a rotatable grinding wheel and a work support which are movable longitudinally and transversely relative to each other, a reversing mechanism including a reversing lever to cause a longitudinal reciprocatory motion between the 50 wheel and work support, a pawl and ratchet actuated feed mechanism to cause said transverse movement, a self-contained fluid pressure mechanism including a piston and cylinder operatively connected to actuate said pawl and ratchet, a control valve associated with said piston and cylinder, an adjustable detent carried by said reversing lever, and means to adjust the position of said detent to vary the movement of the control valve when actuated by the reverse 60 lever to vary the speed of the transverse feeding movement when the reversing lever is shifted to change the direction of said longitudinal movement.
